Four Photographs of Two Slide Members, no date known.

Primary Examiner—Prabhakar Deshmukh(74) *Attorney, Agent, or Firm*—Knobbe, Martens, Olson & Bear, LLP(57) **CLAIM**

The ornamental design for a slide member, as shown and described.

DESCRIPTION

FIG. 1 is a perspective view of a slide member of the present invention, illustrating the slide member in connection with a track system;

FIG. 2 is a front elevational view of the slide member;

FIG. 3 is a right side elevational view of the slide member;

FIG. 4 is a left side elevational view of the slide member;

FIG. 5 is a top plan view of the slide member;

FIG. 6 is a back elevation view of the slide member; and,

FIG. 7 is a bottom plan view of the slide member.
The broken lines are for illustrative purpose only and forms no part of the claimed design.**1 Claim, 2 Drawing Sheets**## U.S. PATENT DOCUMENTS
